UNITED STATES PATENT OFFICE.

DON A. MICKLESON, OF NEW YORK, N. Y.

SAW.

1,355,683.

Specification of Letters Patent. Patented Oct. 12, 1920.

Application filed April 8, 1919. Serial No. 287,249.

To all whom it may concern:

Be it known that I, DON A. MICKLESON, a citizen of the U. S., residing at New York, county of New York, and State of New York, have invented certain new and useful Improvements in Saws, of which the following is a specification.

This invention relates to portable power saws, being intended more particularly for use in mines for cutting timbers and beams.

The invention has for an object to provide a portable power saw characterized by simplicity and cheapness of construction, compact arrangement of parts, and facility of application to the beams or other work to be cut.

For further comprehension of the invention, and of the objects and advantages thereof, reference will be had to the following description and accompanying drawings, and to the appended claims in which the various novel features of the invention are more particularly set forth.

Figure 1 of the drawings is a side view of a portable power saw constructed according to my invention.

Fig. 2 is a plan view thereof.

Fig. 3 is a transverse section on the line 3—3 of Fig. 2.

Fig. 4 is a detail longitudinal axial section of one of the cylinders for moving the slideable saw frame.

I have here shown my improved saw as mounted on a truck 1 supported by wheels 2 adapted to run on truck rails 3 such as are found in mines.

A pair of timbers 4 are mounted on the truck and extend parallel to one another and transversely of the truck, the upper faces of these timbers forming slideways, and being inclined as shown. These timbers may be secured to the truck by U-bolts 6 which are located in grooves 7 in the timbers and extend through the truck floor at their ends, upon which nuts 8 are threaded.

Upon these timbers is mounted a sliding frame which carries a circular saw 9 and an air or other motor 10.

This frame comprises a pair of side members, or runners, 11 which rest on the timbers and may be held against lateral displacement by extensions 12 formed on their lower faces which project down into engagement with the sides of the timbers. These runners 11 are rigidly secured together by a connecting platform 13 which extends be-

tween the rear halves thereof and supports the motor 10, which may be secured thereto by the bolts 14 or other suitable means.

The saw 9 is fixed to a shaft 15 journaled at its ends in brackets 16 secured to the forward end of the runners 11 and may be operatively connected to the motor 10, which is shown as of the reciprocating type, by means of a gear pinion 17 fixed to the shaft 15 and meshing with a gear 18 journaled in a bracket 19 fixed to the inside of one of the runners 11 and having eccentrically connected thereto one end of a connecting rod 20 whose opposite end may be connected to the piston rod of the motor in the usual manner. The motor may be connected by a flexible pipe 21 to any suitable source of compressed air.

The frame carrying the saw may be moved along the slideways to advance the saw to the work by means of a bail 22 connected to the forward end of the frame and to which is attached a rope 23. As a guard for the saw I may provide a plurality of arched bars 28 which are fastened at their ends as by the screws 29 to the outer faces of the slideways 4. These bars may be connected by one or more strips 20, forming a cage for the saw.

A pair of air cylinders 60 are secured upon the upper faces of the timbers 4, as by bolts 61 passing through flanges 62 and extend along beside the members 11 on the cylinder heads 62'. Each cylinder has a piston 63 therein whose piston rod 63' is secured to a lug 64 fixed to the adjacent side member 11, a coiled spring 65 surrounding the piston rod within the piston. Compressed air may be fed to the cylinders by pipes 66 causing the piston to move in a direction to advance the saw to the work at the same time compressing the springs 65 which act to withdraw the saw when the air is released from the cylinder in any well known manner.

Having thus described my invention and set forth the manner of its use, what I claim is new and desire to secure by Letters Patent, is:—

1. A portable power saw comprising a wheeled truck having a pair of timbers extending transversely thereof, the upper faces of said timbers forming slideways, a frame comprising a pair of side runners slideable on said slideways, a saw and a power mechanism therefor mounted on said frame, and

a pair of piston and cylinder devices extending beside said runners and connected thereto and to the said timber for advancing the said saw.

- 5 2. A portable power saw comprising a wheeled truck having a pair of timbers extending transversely thereof, the upper faces of the said timbers being inclined longitudinally and forming slideways, a frame comprising a pair of side runners slideable on said slideways, a saw and a power mechanism therefor mounted on said frame, a pair
- 10

of cylinders secured to said timbers and extending along beside said runners, said cylinders having their piston rods secured 15 at their outer ends to said runners, said cylinders being adapted to be connected at one end to a source of power fluid supply whereby the saw is advanced, and springs surrounding the said piston rods in the said 20 cylinders whereby the saw is retracted.

In testimony whereof I have affixed my signature.

DON A. MICKLESON.
